UNITED STATES PATENT OFFICE

IRVING G. SCOTT AND MAUD C. FOX, OF NEW YORK, N. Y.

DESIGN FOR A WALL POT HOLDER

Application filed September 22, 1931. Serial No. 41,189. Term of patent 7 years.

To all whom it may concern:

Be it known that I, IRVING G. SCOTT, a citizen of the United States, residing at New York city, in the county of New York, State of New York, and I, MAUD C. Fox, a citizen of the United States, residing at New York city, in the county of New York, State of New York, have invented a new, original, and ornamental Design for a Wall Pot Holder, of which the following is a specification, reference being had to the accompanying drawings, forming part thereof.

We claim:

The ornamental design for a wall pot holder as shown.

IRVING G. SCOTT.

MAUD C. FOX.
